UNITED STATES PATENT OFFICE.

LEVI VAN VLIET AND FRANK O'NEIL, OF POMONA, CALIFORNIA.

GAS-GENERATOR.

1,094,762.

Specification of Letters Patent. Patented Apr. 28, 1914.

Application filed October 24, 1912. Serial No. 727,603.

To all whom it may concern:

Be it known that we, LEVI VAN VLIET and FRANK O'NEIL, both citizens of the United States, residing at Pomona, in the 5 county of Los Angeles and State of California, have invented new and useful Improvements in Gas-Generators, of which the following is a specification.

This invention relates to gas generators 10 for use in furnaces and fire-boxes of different kinds, among which may be mentioned the fire-boxes of ordinary cooking and heating stoves, ranges and the like, and in particular discloses certain improvements on 15 the invention made by said Levi Van Vliet, and described in Letters Patent No. 937,341, for a gas generator.

An object of this invention is to minimize the leakage of high pressure gas from the 20 retort, and to this end we construct our retort, wherever possible, with brazed joints rather than screwed joints.

Another object is to provide an efficient 25 heat-conducting retort which can be brought to the generating temperature and started in minimum time. To this end our retort is constructed of any thin strong metallic pipe, preferably steel boiler tubing, and formed with flat inscribed faces on the side adjacent 30 the generating pan.

Another object is to utilize any surplus 35 heat in the auxiliary heating flame, and to that end we provide deflecting means at the ends of the retort which direct the plus heat toward the body to be heated by 40 said generator.

Another object is to provide suitable 45 means for mounting the generator whereby the direction of the primary heating flame may be easily changed toward different parts as desired.

Another object is to provide gas regulating 50 means for the primary heating jets whereby the flame issuing therefrom may be completely extinguished or adjusted to suit the convenience of the operator. With this regulating means the generator may be adjusted for various conditions of service giving a smokeless flame at all times.

The accompanying drawings illustrate the 55 invention.

Figure 1 is a front elevation partly in section, and showing the position of the gas regulating means. Fig. 2 is a transverse section along the broken line x^2-x^2 , of Fig. 1 and shows the details of the gas regulat-

ing valve, retort chamber, and heating pan. Fig. 3 shows another form of jet cap with which our generator may be equipped if desired.

1 is a cylindrical generating retort made preferably of thin steel boiler tubing, and provided at its ends with screw-threads 2 adapted to engage threads on the flanged caps 3 and 4 closing the ends of the retort. 60 These caps are constructed with the supporting and flame deflecting flanges 5 merging into the circular fillet 6 on the inner face and into the cylindrical supporting shoulder 7 on the outer face. Below, and supporting the generating retort, is the generator pan 8 having ends 9 provided with the circular seats 10. The retort is revolvably supported on the pan by loosely seating the cylindrical shoulders 7 on the circular 70 seat 10, the flanges 5 lying within the ends and supporting the retort against longitudinal motion along the pan. This advantageous mounting will permit revolution of the retort for a purpose indicated below.

At its lower perimeter and adjacent the generator pan 8, the retort 1 is provided with the inscribed flat faces 11 preferably planed onto the circular tube for the limited distance 12 to 13 in Fig. 1. The metal of the 85 retort is thereby thinned at the faces, and provides very rapid heat conduction from the starting flame kindled in pan 8, to the interior of retort.

The gas-dome 14 is brazed into the upper 90 perimeter of retort 1 and is provided with the downwardly projecting auxiliary heating jets 15 directed onto and along the retort. On the upper screw-threaded extremity 16 of this gas-dome is screwed the 95 valved jet-dome generally indicated by the reference numeral 17, and comprising in the main the needle valve 18, packed valve rod 18', the valve seat 19 and the jet-dome proper 20, provided with any suitable number of gas jets 21. In order that the valve seat 19 may be properly machined, we provide bushing 22, the same being externally threaded to engage the valve casing 23, and internally threaded to receive the adjusting 100 thread 24 on the valve stem 18'. To the threaded extremity 25 of the bushing 22 is screwed the packing cap 26 containing the usual packing 27 surrounding the smoothed cylindrical packing face 28 of the valve 105 stem, space 29 representing the packing clearance for the cap. The jet-dome 20 is

shown provided with three jets 21, this number being found most suitable in practice, but it is understood that any other preferred number may be used without departing from the spirit of our invention herein disclosed.

To supply oil to the retort it is led from the general supply pipe 30 through controlling valve 31 and pipe 32 into the threaded aperture 33 in cap 3. To supply oil to the generating pan, a branch pipe 34 is connected to the main supply pipe 30 and conducts oil through the controlling valve 35 and pipe 36 into the generating pan 8.

In using our improved generator the controlling valve 35 is operated to permit a suitable amount of oil to flow into the generating pan. After igniting this oil its starting or generating flame surrounds the retort 1 and impinges directly onto flat faces 11, preheating the retort preparatory to admission of oil to the same through the pipe 32. By using steel, the retort may be constructed of minimum thickness, and by planing the faces 11 into its lower perimeter the thickness is still further reduced at the critical point adjacent the generating flame. With these provisions the heat from the generating flame is conducted more rapidly to the inner face of the retort and will more rapidly raise its temperature sufficiently high to properly vaporize oil fed to it through pipe 32. With these improvements our retort is heated and ready for action in two minutes, whereas three and one-half minutes is the period required with the usual forms of wrought iron retort. The temperature having been properly raised valve 31 is operated to admit slight continuous flow of oil onto the hot inner face of the retort. This oil being immediately vaporized issues in the form of gas from jets 15 and 21, the valve 19 being open. This gas is lighted and the flames from jets 15 will play continuously onto and along the retort holding it at a high vaporizing temperature even after the starting flame from the generating pan is extinguished while the primary flames issuing from jets 21 provide most of the available heat and may be directed against the face of a stove, fire-box or other surface as desired. To properly align the primary flame onto the exact point to be heated, the valve wheel α and the extended valve rod 18' are used as a handle to rotate the retort on seat 10 of the generating pan until jets 21 have the correct elevation for directing their flame to the point desired. During operation the pressure of the vaporized gas in the retort is considerable, and with the old forms of gas-dome affixed to the retort by a screw connection, it is difficult to avoid leakage of the gas past the threaded joints. In our improved construction, however, the gas-dome 14 is brazed onto the retort and all such difficulty is avoided. The flame

issuing from the auxiliary heating jets 15 is often more than sufficient to heat the retort and after passing along the full length of same this surplus is deflected by rounded fillets 6 and upright flanges 5 along dotted line 38 toward any surface which it is desired to heat.

In the old construction the primary flame from jets 21 and the auxiliary flame from jets 15 were all simultaneously adjusted at the main oil supply valve 31. When it happened that a small amount of heat only was required, the flames from all jets were simultaneously and proportionately reduced to a point where annoyance was frequently encountered due to the smoky and the sooty character assumed by the small flame. To obviate this difficulty and make the flame adjustment more flexible and satisfactory, our improved construction is provided with a needle valve 18 whereby the flame from the primary heating jets may be adjusted or extinguished independent of the auxiliary heating flames which continue with good volume and pressure regulated only by the oil valve 31. When the primary flame from the jets 21 is reduced so low that it smokes, the same is extinguished and the deflected surplus heat of the auxiliary flames is utilized to do the little heating required at this time. By this means it will be seen that between the main valve 31 and the needle valve 19, flexibility of adjustment and flame control is secured which insures combustion free of all smoke at every point in the adjustment. Our generator is also supplied with the usual jet-dome 39 shown in Fig. 3, which may be screwed onto gas-dome 14 in place of the valved jet-dome 17 shown in Figs. 1 and 2, the former being used at the option of the operator when no delicate adjustment is to be made.

We claim:—

1. A gas generator comprising an elongated retort, jets communicating with said retort and directed onto and along the same, and flanged caps at the ends of said retort for deflecting the flame produced by said jets from said retort.

2. A gas generator comprising an elongated tubular retort, a gas dome on the retort, jets mounted on said dome and directed onto the retort, caps on the ends of said retort and provided with flanges for deflecting the flame issuing from said jets, and means for feeding oil to the retort.

3. A gas generator comprising an elongated tubular retort, jets mounted above and directed onto the retort, caps closing the ends of the tubular retort, said caps being provided with flame deflecting flanges, a generating pan below the retort and adapted to coöperate with the flanged caps to revolvably support the retort, and means for feeding oil to the retort.

4. A gas generator comprising a thin elongated cylindrical retort the circumference being provided at one side with flat faces serving to thin the metal at that side, 5 a generating pan adjacent the said flat faces, and means for feeding oil to the retort.
5. A gas generator comprising a thin elongated cylindrical retort, a gas-dome on same, jets mounted on said dome and directed onto 10 the retort, a generating pan for the retort, and flat faces on the retort adjacent the generating pan.
6. A gas generator comprising a tubular retort, jets communicating with said retort 15 and directed onto and along same, flanged caps at the ends of said retort, the flanges serving to deflect the flame of the aforesaid jets, a gas regulating valve, and jets communicating with the retort through said 20 valve.
7. A gas generator comprising a tubular retort, jets communicating with said retort and directed onto and along same, flanged caps at the ends of said retort the flanges 25 serving to deflect the flame of the aforesaid jets, a gas regulating valve, jets communicating with the retort through the said valve, and valved means for feeding oil to the retort.
- 30 8. A gas generator comprising a tubular retort, a gas-dome mounted on same, jets mounted on said dome and directed onto the retort, a cap mounted on said dome, the said cap being provided with gas jets, and a valve 35 for regulating the amount of gas fed to the last said jets from the gas-dome, caps on the end of said retort, the caps having flame deflecting flanges.
9. A gas generator comprising a horizontal tubular retort revolvably mounted, a gas-dome radially mounted on the retort, jets on 40 said dome directed along and onto the said retort, a needle valve mounted on said dome, the valve having a horizontal valve rod and port running perpendicular to the tubular 45 retort, and gas jets communicating with the retort through said valve.
10. A gas generator comprising a retort, a jet communicating with said retort and directed onto and along same, a deflector 50 near the end of said retort, said deflector being adapted to deflect the flame produced by said jet away from said retort, a valve, and a jet communicating with said retort through said valve.
11. A gas generator comprising a tubular retort revolvably mounted, a gas dome mounted on the retort, a jet on said dome directed along and onto said retort, a valve mounted on said dome, and gas jets communicating 60 with said dome through said valve.

In testimony whereof, we have hereunto set our hands at Los Angeles, California, this 18th day of October, 1912.

LEVI VAN VLIET.
FRANK O'NEIL.
